UNITED STATES PATENT OFFICE.

JOHN G. FOGARTY, OF WEST WEBSTER, NEW YORK, ASSIGNOR OF ONE-FOURTH TO SWEENEY AND BOLAND, OF ROCHESTER, NEW YORK, A COPARTNERSHIP CONSISTING OF MICHAEL E. SWEENEY, AND PATRICK T. BOLAND.

APPARATUS FOR DRIVING RAILROAD SPIKES.

Application filed April 19, 1926. Serial No. 103,163.

The object of this invention is to provide an apparatus adapted to locate and guide railroad spikes while they are being driven into the ties to fasten the rails in place thereon.

This and other objects of this invention will be fully illustrated in the drawings described in the specification and pointed out in the claims at the end thereof.

10 In the accompanying drawing:

Figure 1 is a top plan view of the apparatus as it appears attached to a rail.

Figure 2 is an end elevation of the apparatus as it appears when attached to a rail.

15 Figure 3 is a side elevation of the apparatus and a portion of the rail to which it is attached.

Figure 4 is a detail view of the guiding jaws of the apparatus.

20 In the several figures of the drawings like reference numerals indicate like parts.

The apparatus forming the subject matter of my present invention is adapted to locate, hold and guide railroad spikes while 25 they are being driven into the ties alongside the rail to fasten the base of the rail to the ties. The apparatus is mounted to and supported on the rail to be fastened to the tie to locate the spikes in a predetermined position with relation thereto.

As illustrated in the figures the apparatus comprises a substantially rectangular frame 1 with the boss 2 formed thereon and overhanging on one side thereof. This boss is 35 hollow having a rectangular hole thru it to form a guide sleeve that projects below the frame 1 and is held adjacent to the rail as will hereinafter appear. The guide sleeve thus formed also projects slightly above the 40 frame and the opening in the top is flared outwardly to provide a funnel shaped entrance for the guide sleeve into which a spike can readily be dropped and the ram for driving it in place inserted therein.

45 On the under side of the frame 1 on the opposite side to the guide sleeve formed in the boss 2 are pivoted the supporting jaws 3 and 4. Each of these jaws comprises the radial arms 5, 6 and 7 projecting from a common center and mounted on the stud 8. The stud 8 projects thru the frame 1 and its reduced end is threaded to receive the locknut 9. A suitable handle 10 is keyed or otherwise suitably fastened to the stud and

held in place by the locknut 9 so that the 55 stud and its jaw can be readily rotated therewith. The three radial arms comprising a supporting jaw are of different lengths and each is provided with a rectangular shoulder on the under side thereof. These shoulders are located at varying elevations with relation to one another as well as at varying distances from the center of rotation of the jaw. These supporting jaws on one side, the back or face 11 of the boss 2 and the top of 60 the frame 1 form a saddle that engages over the head 12 of the rail 13 to support the apparatus thereon.

The different supporting shoulders on each jaw are provided because the rails differ in 70 size and weight. Thus the angular shoulder formed in the radial arm 5 when turned at right angles to the rail 13 will fit over the head of a rail of one size and support the apparatus between this shoulder and the inside of the boss 2 on top of the rail at a predetermined elevation from the base thereof as illustrated in Figure 2. The other jaws with their shoulders accommodate different 75 sizes of rail head between them and the boss 80 and support the apparatus in a corresponding elevation thereon.

To prevent the apparatus from tilting on the head of the rail a locking finger or bar 14 is used. Two such locking bars or fingers are provided on the apparatus one on each side of the boss 2. The lower portion of each of the locking bars is bayonet shaped so as to extend from the bearing in the side of the boss 2 around the corner of the boss 90 to the middle of the back thereof, in order to engage the web of the rail at a point intermediate of the two ends of the apparatus as illustrated in Figure 1. Two locking fingers are provided to mount the apparatus on 95 rails having different webs, or if necessary mount the apparatus at a point on the rail having a splice bar attached to the web thereof. The outer end of the bayonet shaped locking bar is flattened so as to make good 100 contact with the web of the rail and guide the apparatus in conjunction with the supporting jaws when it is moved from one position to another over the top of the rail. Each of the locking bars is provided with a vertical extension 15 with an angular projection 16 at the top thereof forming the handle for rotating the locking bar. The 105

vertical extension is mounted to rotate in the bearings 17 and 18 part of which are formed in the side of the boss 2 while the other half is formed in the bearing block 19 fastened to the side of the boss by means of the cap screws 20, 20. A spring finger 21 is mounted on the bearing block 19 and yieldingly rests against the vertical extension of the locking bar at a point adjacent to the pin 22 projecting from the vertical extension. When the locking bar is rotated to be moved away from the web of the rail this pin swings against the spring finger and yieldingly resists its movement until it is located directly under it, in which position the locking bar is out of engagement with the web so that the apparatus can be lifted from the rail. On the other hand after the apparatus is again placed on the rail and the locking bar is rotated in engagement with the web the spring finger forces the pin away from it until it is out of engagement therewith and the end of the bar rests solidly against the web of the rail.

25 The guide sleeve formed in the boss 2 is assisted in locating a spike on the tie alongside of the rail by the spring pressed jaws 25 and 26. These jaws are pivoted on the pivot pins 27 and 28 provided in the front 30 of the boss 2. These jaws project down on the outside of the boss and under it where they are provided with sloping faces 29 and 30 on the inside thereof. These sloping faces are located at the bottom of the guide sleeve and form an inwardly sloping continuation of a portion of the opposing side walls thereof. In the sloping faces of the jaws are provided the opposing rectangular notches 31 and 32 which are adapted to embrace the lower end of a spike and hold it in an upright position in the guide sleeve as illustrated in Figure 2. The portion of the jaws 25 and 26 projecting under the boss also slope toward the inner end of the notches as illustrated in Figures 1 and 2 and provide a sloping shoulder 33 at the inner end of the sloping faces 29 and 30.

35 A short extension 35 on the jaws 25 and 26 projects above the pivot pins 27 and 28 and in each of these extensions is formed a pocket 36 adapted to receive the end of an expansion spring 37 that is placed between them. This expansion spring normally holds the jaws against the stop 38 which projects from the boss 2 and overlaps a portion of the front of each of the jaws forming guides therefor. When a spike is dropped into the guide sleeve the lower end slips thru between the notches 31 and 32 until the end of the spike rests on top of the tie alongside of the base of the rail. The supporting mechanism heretofore described supports the apparatus in such a way on the rail that the point at which the end 65 of the spike strikes the tie is properly spaced

from the base of the rail so that the head of the spike overlaps the base of the rail in a predetermined manner and securely anchors the rail to the tie.

The notched jaws 25 and 26 hold the 70 spike in an upright position in the guide as above pointed out so that it can be driven into the tie in this position. This is done by means of the ram 40 carried by and operated by an air or electric hammer (not 75 shown). This ram is held to project into the guide sleeve and engages the head of the spike and gradually hammers the spike thru the guide sleeve into the tie.

When the head of the spike reaches the 80 inwardly sloping faces of the jaws 25 and 26, they are forced apart by it against the resistance offered by the expansion spring 37. This, however, does not interfere with the passage of the head past the jaws while 85 it is driven thru by the ram and as soon as the ram is withdrawn after the spike has been driven into the tie the expansion spring 37 brings the two jaws back to their normal position ready to have the next spike 90 inserted between them.

A handle 41 in the form of a bale is attached to the top of the frame of the apparatus by means of which it may be lifted out of engagement with the rail or placed 95 onto it.

I claim:

1. In an apparatus for locating and guiding railroad spikes, the combination of a supporting frame, a guide sleeve on one 100 side of said frame, a supporting jaw at the other side of said frame, and a pair of yielding jaws mounted at the lower end of said guide sleeve, said yielding jaws being adapted to hold a spike in an upright position in said guide sleeve and locate the end of said spike in a predetermined position on the tie with relation to the base of the rail.

2. In an apparatus for locating and guiding railroad spikes, the combination of a 110 supporting frame, a guide sleeve at one side of said frame, a supporting jaw at the other side of said supporting frame, a locking finger, said sleeve and locking finger being adapted to engage one side of a rail and said supporting jaw being adapted to engage the opposite side of the rail, and means to temporarily hold a spike in a vertical position in said sleeve and locate the end of the spike in a predetermined position on the tie with 120 relation to the rail.

3. In an apparatus for locating and guiding railroad spikes, the combination of a supporting frame, a guide sleeve on one side of said frame, a pair of supporting jaws on the other side of said supporting frame, means for adjusting said jaws to straddle rail heads of varying dimensions between them and said guide sleeve, and means for holding a spike in a vertical posi- 130

tion in said guide sleeve and locating it on the tie in a predetermined position with relation to the rail.

4. In an apparatus for locating and guiding railroad spikes, the combination of a supporting frame, means for adjustably supporting said supporting frame in a predetermined position on top of a rail, a guide sleeve, and a pair of swinging jaws mounted below said guide sleeve and adapted to hold a spike in a vertical position in said guide sleeve.

5. In an apparatus for locating and guiding railroad spikes, the combination of a supporting frame, means for adjustably supporting said supporting frame in a predetermined position on top of a rail, a guide sleeve, a pair of swinging jaws mounted below said guide sleeve and adapted to hold a spike in a vertical position in said guide sleeve, and inwardly slanting sides on said jaws to allow the head of the spike to spread said jaws and pass thru between them.

6. In an apparatus for locating and guiding railroad spikes, the combination of a supporting frame, adjustable means carried on the under side of said supporting frame to engage different size rail heads and correspondingly different size rail webs and hold said supporting frame rigidly and in a predetermined position in place on these different size rails, and means for holding and guiding a railroad spike provided on one side of said supporting frame.

7. In an apparatus for locating and guiding railroad spikes, the combination of a supporting frame, a supporting jaw pivoted on the under side of said supporting frame, radial arms of varying length projecting from said supporting jaw, a shoulder on the under side of each of said arms at varying elevations with relation to one another and varying distances from the center of rotation of said supporting jaw, a rigid

member on said frame opposite to said supporting jaw, said shoulders and rigid member adapted to engage between them rail heads of varying size, and means for rotating said jaw to present the proper shoulder to the rail head and hold said supporting frame in place on the rail.

8. In an apparatus for locating and guiding railroad spikes, the combination of a supporting frame, supporting jaws on the under side of said frame, a guide sleeve depending from said frame, and a pair of yielding jaws mounted to swing on said sleeve and projecting across the open end of said sleeve, and having grooves adapted to hold a spike in an upright position, said jaws being forced apart by the head of the spike when it is forced thru between them.

9. In a spike holding and locating device, the combination of a supporting frame, a saddle formed on said frame and adapted to hold said frame in place on the head of a rail, arms pivotally mounted on the side of said supporting frame, jaws provided on said arms, and means for yieldingly holding said jaws in a predetermined position to hold a spike in a predetermined position between them when placed between the jaws.

10. In a spike holding and locating device, the combination of a supporting frame, a saddle formed on said frame and adapted to hold said frame in place on the head of a rail, arms pivotally mounted on the sides of said supporting frame, a jaw provided on each of said arms, a channel provided in each of said jaws, and means for yieldingly holding said jaws together with an opening formed by said channels adapted to receive the shank of a spike and hold this spike in a predetermined position on one side of the rail.

In testimony whereof I affix my signature.

JOHN G. FOGARTY.
